UNITED STATES PATENT OFFICE

EINAR G. HALLQUIST, OF EDWARDSVILLE, ILLINOIS, ASSIGNOR, BY MESNE ASSIGNMENTS, TO GENERAL STEEL CASTINGS CORPORATION, OF GRANITE CITY, ILLINOIS, A CORPORATION OF DELAWARE

RAILWAY TRUCK

Application filed February 11, 1928. Serial No. 253,636.

My invention relates to railway rolling stock and consists in a novel truck structure adapted to be used for heavy duty.

One object of my invention is to reduce the wheel load and this object is accomplished by providing four axles and eight wheels instead of two or three axles and four or six wheels.

Another object of my invention is to make the wheel base as short as possible, thereby reducing the extent which the body overhangs the center plate and also reducing the necessary side play of the axles in their journals. I attain this object by placing the middle wheels of the truck very close to each other.

Such arrangement makes it difficult to provide brake heads and other brake gear between the middle wheels and another object of my invention is to provide sufficient braking area, which object I attain by providing clasp brakes on the end wheels of the truck and single brakes on the outer portions of the intermediate wheels of the truck.

Another object of my invention is to provide a bolster especially adapted for heavy duty and is partially attained by making the center portion of the bolster of deeper and stronger cross section (such as a box cross section) than ordinarily. The spaced intermediate axles of an eight wheel truck readily accommodate such a bolster and where the bolster may be elevated sufficiently to clear an underlying axle, a bolster with such a center portion may be used on a six wheel truck.

Another object of my invention is to provide a simple truck frame supporting equalizing system which eliminates bending moments at the center of the wheel piece due to vertical loads. I attain this object by providing independent equalizing systems for each pair of axles and by supporting the truck frame at a plurality of points along its length.

The above and various other more detailed objects are attained by the structure illustrated in the accompanying drawings, in which—

Figure 1 is a one-half longitudinal top 9 supports the truck through a hanger 21 and 100

view of a truck embodying a preferred form of my invention.

Figure 2 is in part a side elevation of and in part a section on the longitudinal center line of the structure shown in Figure 1.

Figure 3 is a side elevation, largely diagrammatic, illustrating the brake rigging applied to the truck shown in Figures 1 and 2, the rigging being omitted from Figures 1 and 2 for the purposes of more clearly illustrating the other structure.

Figure 4 is a transverse section on the line 4—4 of Figure 1.

Figure 5 is a one-half end view of the truck.

Figures 6 and 7 correspond to Figures 1 and 2 but illustrate a modified form of my invention in which the center bolster is integral with the truck frame.

Figure 8 is a one-half longitudinal top view and

Figure 9 is a side elevation of a four wheel truck embodying some of the features of my invention, part of the structure being broken away in Figure 9 to more clearly illustrate other parts of the structure.

Figure 10 is a vertical transverse section on line 10—10 of Figure 9.

The truck illustrated in Figures 1 to 5 comprises four axles 1, 2, 3, and 4 mounted on wheels as indicated at 5, 6, 7, and 8 and carrying the usual journal boxes, not shown, on which are supported leaf springs 9 and 10 which, as readily understood, will be duplicated on the righthand end of the truck. These springs support the truck frame comprising wheel pieces 11, cross transoms 12 with lateral flanges 12^a, and end rails 13 and suitable brake hanger brackets 14, equalizer fulcrums 15, spring caps 16, and other details as may be desired.

The springs support the frame through an equalizing system including equalizers 17 suspended from the springs by links 19 and positioned between the sides of the box-shaped wheel pieces 11 and fulcrumed thereon as indicated at 18. The inner end of each spring 10 is anchored directly to the wheel piece by a hanger 20 located near the longitudinal center of the truck and the outer end of spring

a coiled spring 22 seated on cap 23 carried by the hanger.

It will be noted that the spring system indicated in the side elevation portion of Figure 2 is connected to the frame independent of the similar spring system on the other end of the truck. It will also be noted that each of these spring systems supports the truck frame at a point near its ends, at a point intermediate the wheels 5 and 6, and at a point near the center of the truck.

The superimposed load is transmitted to the truck frame by means of a center bolster comprising a center portion 24 having a general box-shaped cross section and located between axles 2 and 3 and projecting downwardly into the space between these axles. This center bolster is provided with box-shaped arms 25 which extend upwardly from the center portion to clear axles 2 and 3 and then project downwardly and outwardly so as to extend under the transoms 12 from which the center bolster is supported by means of links 26, the lower ends of which engage pins 27 seated in spaced bearings 28 provided on the box-shaped ends of the center bolster arms 25. This arrangement places the supporting pins in double shear similar to the arrangement for the pins 29 at the upper ends 30 of links 26. This arrangement also provides a maximum amount of strength for the center bolster arms and avoids the likelihood of failure of these center bolster members when heavily loaded.

Referring to Figure 3, it will be seen that the brake gear includes six shoes 30 applied to the wheels on one side of the truck which affords the same braking surface as has been provided in six wheel trucks with clasp brakes. The brakes are so arranged, however, that the middle wheels 6 and 7 only have brakes applied to their outer faces or the faces nearest the ends of the truck, and this enables the two middle wheels to be placed so close together that they merely clear each other. The space between wheels 5 and 6 and wheels 7 and 8 must be large enough to provide clearance for the transom members and this clearance is sufficient to accommodate 50 brake rigging applied to each of the wheels. This drawing also indicates the suspension of the brake hangers 31 from the brackets 14 which are formed integrally on the truck frame.

In the modification illustrated in Figures 6 and 7, the same axle and wheel arrangement is used but the truck frame includes an integrally formed center bolster having the 60 box-shaped center portion 32 with box-shaped arms 33 united with the box-shaped transoms 34. Otherwise the truck construction is substantially the same as the preferred form illustrated in Figures 1 to 5 and I retain 65 the advantages inherent in the close coupling

of the middle wheels and in the independent spring systems on each side of the truck.

In the construction illustrated in Figures 8, 9, and 10 I show a four wheel truck in which the frame, supported by springs 41 mounted on equalizers 42, includes spaced transoms 35, each box-shaped in cross section, and pivoted supporting links 36. The truck bolster 37 is box-shaped in cross section and has depending portions 38 at its ends, which depending portions are provided with laterally extending arms 39 box-shaped in cross section and providing spaced bearings for the pins 40 by which the bolster is supported by links 36.

In both of the link suspensions illustrated, the pins at both ends of the links are placed in double shear and the bolster arms are shaped to provide the greatest amount of strength for a given weight of metal.

Obviously, many variations in the details of the truck structure may be made without departing from the spirit of my invention, and I contemplate the exclusive use of all of the features of my truck, however used, which come within the scope of my claims.

I claim:

1. In a railway truck, eight wheels mounted on four axles, the two middle axles being nearer to each other than to the end axles, clasp brakes on the wheels of the end axles and single brakes on the faces of the wheels of the middle axles nearest to said end axles.

2. In an eight wheel truck, a frame including wheel pieces with pedestals for four axles, spaced cross transoms and transverse end rails between said wheel pieces, and brake hanger brackets formed integrally on said transoms and end rails for mounting brakes on both sides of the end wheels and at the outer side of each middle wheel.

3. In a railway truck, a rigid truck frame, two pairs of axles, transoms across and rigid with said frame between the axles of each of said pairs, and a truck bolster between said pairs and supported by said transoms.

4. In a railway truck, a truck frame, two pairs of spaced axles, transoms across said frame between the axles of each of said pairs, and a center bolster having arms extending beneath and supported from said transoms.

5. In a railway truck, a truck frame, two pairs of spaced axles, transoms across said frame between the axles of each of said pairs, and a center bolster having arms extending beneath and swingingly suspended from said transoms.

6. In a railway truck, a frame including spaced cross transoms, and a truck bolster having a box-shaped body with arms extending longitudinally of the truck and carried by said transoms.

7. In a railway truck, a frame including spaced cross transoms, and a truck bolster having a box-shaped body with box-shaped

- arms extending longitudinally of the truck and carried by said transoms.
8. In a railway truck, a frame including spaced cross transoms box-shaped in cross section, and a truck bolster having a box-shaped body with box-shaped arms extending longitudinally of the truck and carried by said transoms. 70
9. In a railway truck, a frame including 10 wheel pieces box-shaped in cross section, spaced transoms connecting said wheel pieces and box-shaped in cross section, and a truck bolster having a box-shaped body with box-shaped arms extending longitudinally of the truck and carried by said transoms. 75
10. In a railway truck, a frame including spaced cross transoms, axles spaced from the center of the truck, a truck bolster between said axles, and box-shaped arms on said bolster extending over said axles and connected to said transoms. 80
11. In a railway truck, a frame including spaced cross transoms, axles spaced from the center of the truck, a truck bolster between 25 said axles, and box-shaped arms on said bolster extending upwardly over said axles and then downwardly beneath said transoms and supported from the latter. 85
12. In a railway truck, a single truck frame 30 including wheel pieces and spaced cross transoms, two pairs of wheeled axles with journal boxes, equalizers supported from said journal boxes and fulcrumed on and supporting said wheel pieces adjacent said transoms, and a truck bolster carried by said transoms. 90
13. In a railway truck, two pairs of axles 35 with wheels and journal boxes thereon, equalizers carried by the respective journal boxes of each pair of axles, and a frame including cross transoms positioned between the axles of each of said pairs, said frame being carried by said equalizers adjacent said transoms. 95
14. In a railway truck, a single truck frame, two pairs of axles journalled in pedestals rigid with said frame, and independent equalizing systems for supporting said frame from each of said pairs of axles. 100
15. In a railway truck, two pairs of axles, 40 journal boxes, a frame with hollow wheel pieces, and equalizers housed in said wheel pieces between the axles of each of said pairs, said equalizers being fulcrumed to and supporting said wheel pieces and carried on said journal boxes. 105
16. In a railway truck, two pairs of axles, 45 journal boxes, a frame with hollow wheel pieces, and equalizers housed in said wheel pieces between the axles of each of said pairs, said equalizers being fulcrumed to and supporting said wheel pieces and carried on said journal boxes by means of springs housed in said wheel pieces. 110
17. In a railway truck, a single frame, four 50 axles, and an equalizing system supporting said frame at points spaced longitudinally of the truck and located respectively outside of the end axles, between the middle axles and between the middle axles and the end axles. 115
18. In a railway truck, a single frame, four 55 axles and two independent equalizing systems, each supporting said frame at points spaced longitudinally of the truck and located respectively outside of the end axles, between the middle axles, and between the middle axles and the end axles. 120
19. In a railway truck, a frame, spaced 60 transoms with lateral flanges, a plurality of axles between said transoms and spaced so closely that their adjacent wheels barely clear each other and project under said flanges, and axles on the outer sides of said transoms and spaced from said first-mentioned axles sufficiently for their wheels to accommodate said transoms between them. 125
20. In a railway truck, a frame, spaced 65 transoms, a plurality of axles between said transoms and spaced so closely that their adjacent wheels barely clear each other, and axles on the outer sides of said transoms and spaced from said first-mentioned axles sufficiently for their wheels to accommodate brake gear between them. 130
21. In a railway truck, a frame, spaced 70 transoms, a plurality of axles between said transoms and spaced so closely that their adjacent wheels barely clear each other, and axles on the outer sides of said transoms and spaced from said first-mentioned axles sufficiently for their wheels to accommodate said transoms and brake gear between them. 135
22. A railway truck bolster having a load 75 supporting portion and supporting arms extending therefrom upwardly and outwardly so as to clear truck axles and then downwardly and outwardly so as to extend under truck transoms. 140
23. In a railway truck, a truck frame including spaced transoms box-shaped in cross 80 section, a bolster between said transoms having legs extending beneath said transoms and box-shaped in cross section, and hangers between the sides of said transoms pivotally suspending said bolster legs. 145
24. In a railway truck, two pairs of axles, 85 a frame with hollow wheel pieces, and two equalizing systems housed in said wheel pieces between the axles of each of said pairs respectively. 150
25. In a railway truck, a frame including 90 spaced cross transoms, axles spaced from the center of the truck, a truck bolster between said axles and having a box-shaped cross section, and box-shaped arms on said bolster extending upwardly over said axles and downwardly beneath said transoms and supported from the latter. 155
26. In a frame for a railway truck, wheel 95 pieces with pedestals for the truck axles, 160

transverse end rails, and spaced cross transoms extending between said wheel pieces and located between said end rails, the pedestals for two of said axles being located between the ends of said transoms.

5 27. A one piece frame for a railway truck comprising wheel pieces with pedestals for the truck axles, end rails and cross transoms integral with said wheel pieces, the pedestals for two of said axles being located between 10 the ends of said transoms.

28. In a railway truck, a frame including spaced cross transoms, axles spaced from the center of the truck, a truck bolster between said axles, and arms on said bolster extending 15 over said axles and connected to said transoms below the tops thereof.

29. In a railway truck, a one-piece truck frame including transverse transoms, two 20 pairs of axles, the axles of each pair being on opposite sides of a respective transom, and a truck bolster located between said pairs of axles and supported by said transoms.

30. In a railway truck, a truck frame including four pairs of pedestals rigid with the 25 frame, two pairs of axles journalled in said pedestals and two spring equalizing systems independently anchored to said frame, each system supporting said frame from one of said pairs of axles.

30 In testimony whereof I hereunto affix my signature this 25th day of January, 1928.

EINAR G. HALLQUIST.
